UNITED STATES PATENT OFFICE.

ALEXANDER S. HARVEY AND JOSEPH W. BRILL, OF LOS ANGELES, CALIFORNIA,
ASSIGNORS TO WILLIAM R. WALLACE, OF LOS ANGELES, CALIFORNIA.

SHOWER-BATH.

1,111,692.

Specification of Letters Patent. Patented Sept. 22, 1914.

Application filed April 30, 1914. Serial No. 835,383.

To all whom it may concern:

Be it known that we, ALEXANDER S. HARVEY and JOSEPH W. BRILL, citizens of the United States, residing at Los Angeles, in the county of Los Angeles and State of California, have invented a new and useful Improvement in Shower-Baths, of which the following is a specification.

This invention relates to bath tub fixtures and more particularly to shower bath attachments, and the principal object is to provide a shower that is readily applied to the standard bath tub cock.

It is also an object to provide a shower bath that does not require an inclosure to prevent the water from escaping from the confines of the bath tub.

It is also an object to provide a shower in which the plurality of sprinkling elements are adjustably secured so that the spray therefrom is capable of being regulated to meet individual requirements.

It is a further object to provide a branched support for the shower that will fit any one of the numerous styles of bath tub cocks, together with means to properly align the upright member of the shower.

In the drawings accompanying this specification; Figure 1 is a side elevation of the shower showing the same applied to a bath tub, with the latter partly broken away to clearly show the operation of the spraying members. Fig. 2 is a front elevation of one of the spray members showing the preferred arrangement of the openings therein. Fig. 3 is a plan view of the spray member and the valve connection to the upright duct. Fig. 4 is a transverse section of the spray and the valve on a larger scale showing the upper connection. Fig. 5 is a similar section of the middle ported connection for the intermediate spraying member. Fig. 6 is a side elevation, partly in section of the supporting member and its connections to a bath tub cock also in section, and Fig. 7 is a plan view of the same supporting member as applied to a bath tub cock.

More specifically in the drawings numerals are used to designate the different parts, 50 9 designating the tub of a usual standard length having a bath cock 10 with hot and cold water connections joining to a common exit nipple 11.

Bearing upon and engaging with the 55 spherically formed joint 12 of the bath cock,

is the recessed face 14 of the bracket 15 having the laterally extending arms 16 and the dependent limb 17. The horizontally disposed and forwardly projecting portion of the plate 15 is provided with a threaded bore 60 in which the lower threaded end of the lower pipe 18 is secured and preferably extends at right angles to the plane of the bracket and vertically in relation to the tub. To secure the bracket to the bath cock in 65 this desired position, the outer ends of the arms are formed with a lip 19 which prevent the straps 21 from slipping off, the outer or front face being curved as shown in the two planes, the straps being formed to 70 conform to these curves and to the curve of the bath tub cock intermediate the inlet and outlet, this portion being usually constricted as shown. The rear ends of these looped straps 21 are provided with openings 75 through which are passed the bolts 22 to clamp the looped straps and the bracket rigidly to the bath cock. In case the nuts 23 of the cock are too close together, the inner flat face of the arms may rest thereon and 80 form a support, the resultant angle of the clamps engaging the constricted portion of the cock, being accommodated by the curved face of the arms 16.

To regulate and secure the shower in the 85 upright position necessary for the most efficient results, the dependent limb 17 is provided, in the lower portion of which a number of threaded bores are provided, adapted to receive and hold the adjusting screw 25 90 which may only bear upon the nipple 11 but is preferably threaded into and forms therewith a positive connection to the clamp band 26, provided with a threaded bore for the screw 25 and bores in the ends through 95 which is passed the clamping bolt 27. These nipples are found to be of different lengths so the plurality of bores are provided in the stem 17 to accommodate these differences.

The upright duct of the shower is preferably formed of two lengths of tubing, preferably of non-corroding metal, each end of the tubes being threaded, that of the lower 18 being of greater length and extending through the bracket 15 to receive the metal nipple 28 of the flexible connection 29 preferably of pure rubber hose, and provided with a convenient bulb 30 to engage the lower end of the nipple 11 of the bath cock.

To the opposite and upper end of the tube 110

18 is secured the connection and casing 32 of the tapered plug 33 to which is secured the nipple connection formed on the back 31 of the lower spray member 34. This casing 5 differs from the upper casing 35 in that it has a channel 36 which connects with the upper opening in the boss adapted to receive and support the upper tube 37, on the opposite end of which is supported the valve 10 casing 35. This plug valve casing 35 encloses a tapered valve 38 to fit the casing and this valve is provided with a threaded bore from its periphery in which is secured the nipple 39 of the upper spray member 40. 15 These tapered plugs are held in the connection and casing by a screw 41 which engages with a washer 42 bearing on the side of the connection and casing next the smaller end of the tapered or conically formed ported 20 plug and valve, and this screw may be adjusted to lock the plug or valve in the desired position and form a tight joint, it being possible to turn the upper spray member upward as shown in dotted lines in Fig. 25 4 to drain the same, and also to cut off the water from this upper member, when it is desired to use the lower spray member 34 alone. These spray members are preferably formed of a drawn shell 43, formed as 30 shown in Figs. 3 and 4 and concavely curved in the lateral plane, there being a flange formed on this curve to receive the rolled over edge of the perforated face 44, these perforations being punched in any desired 35 configuration so that the water issuing therefrom will not fall outside the tub.

In the operation of this shower the parts are assembled as shown and the two clamps 21 are passed around the cock and the arms 40 16 of the bracket, and the bolts 22 inserted and screwed tight. The screw 25 is then inserted in the preferred bore in the stem 17 and screwed against the nipple until the tubes 18 and 37 are in their correct position, 45 the screw is now withdrawn the thickness of the metal clamp ring at the screw bore and the clamp inserted, with the threaded bore registering with the screw 25, which is now screwed into place, when the screw 27 is 50 tightened to clamp the ring and thus securely fix the position of the uprights of the shower.

Connecting up the hose connection 29 to the lower end of the tube 18 and the nipple 55 11, the water may be turned on and the spray member adjusted to the angle desired to control the fall of the streams of water.

What we claim is—

1. An attachable shower bath comprising an upper and a lower tubular member, means to adjustably secure said lower member to a bath cock, a connection interposed between said upper and lower tubular members and adapted to support and convey fluid to a spraying member, a valve casing secured to the upper end of said upper tubular member and adapted to support and convey fluid to a spraying member, spraying members having concaved apertured faces 70 adjustably supported in said connection and said valve casing, and tubular means to connect the lower end of said lower tubular member to said bath cock.

2. A detachable shower bath comprising an upper and a lower tube, means to vertically adjust and secure the lower end of said lower tube to a bath cock, a flexible connection from said cock to said lower tube adapted to convey fluid thereto, a hollow connection secured to the upper end of said tube and the lower end of said upper tube having a channel adapted to convey fluid through said connection and to a spraying member supported in relation thereto, an elongated spraying member vertically adjustable in said connection, a valve casing secured to said upper end of said upper tube and adapted to convey fluid to a spraying member, and an elongated spraying member vertically movable in relation to said valve casing, whereby the supply of fluid thereto may be cut off as desired.

3. An adjustable shower bath comprising an upper and a lower tube, means to adjust and secure the lower end of said lower tube to a bath cock, a tubular connection from the bath cock to said lower tube, a hollow connection arranged to connect the said upper and lower tubes, provided with a channel to convey fluid, an elongated spraying member extending on either side of said connection and vertically movable in relation thereto, a valve casing secured to the upper end of said upper tube, a tapered valve mounted in said casing adapted to convey fluid to a spraying member, and a spraying member attached to and extending on either side of said valve, and adapted to operate the said valve.

A. S. HARVEY.
JOSEPH W. BRILL.
